UNITED STATES PATENT OFFICE.

FRANK B. KOSA, OF HILLSBOROUGH, WISCONSIN.

PAPER-ROLL HOLDER AND CHANGEABLE TYPE-PRINTER.

SPECIFICATION forming part of Letters Patent No. 498,516, dated May 30, 1893.

Application filed January 16, 1891. Serial No. 377,974. (No model.)

To all whom it may concern:

Be it known that I, FRANK B. KOSA, a citizen of the United States, residing at Hillsborough, in the county of Vernon and State 5 of Wisconsin, have invented certain new and useful Improvements in Paper-Roll Holders and Printers, of which the following is a specification.

This invention relates to roll paper reels 10 and particularly to an attachment for roll paper reels, whereby the paper is printed as it is drawn from the roll.

The object of the invention is to provide an 15 automatic device which will cause only one impression to be made as the paper is pulled from the roll, whether that portion of paper drawn from said roll be long or short.

The invention further consists of certain 20 constructions and combination of parts to effect a perfectly cheap and durable roll paper printer, as will be more fully hereinafter described and claimed.

In the accompanying drawings forming 25 part of this invention, Figure 1 is a perspective view of my improved printing device secured to a paper roll holder. Fig. 2 is a vertical section of the side arms supporting the inking and printing rollers. Fig. 2^a is a diagrammatic view showing the relative arrangement of the rollers and the paper roll. Fig. 3 is a perspective view of the tension rod. Fig. 4 is a perspective of the bar in which the tension bar slides. Fig. 5 is a top plan view of the base plate in which the side arms are adjustably secured. Fig. 6 is a front elevation 30 of the printing roller showing at each end the automatic device, and the semi-circular bridge pieces over the non-printing space of such roller. Fig. 7 is a detached end view of one 35 of the bridge pieces. Fig. 8 is a cross section of the printing roller. Fig. 8^a is an enlarged plan view of the inner side of a protecting plate. Fig. 9 is an end view of the printing roller showing the automatic mechanism in 40 normal position after the previous impression has been printed. Fig. 10 is an end view of the printing roller and paper roll in dotted lines, with the toothed wheel engaging the paper roll and the segment. Fig. 11 is a similar 45 view, with the parts moved on by pulling the paper. Fig. 12 is a similar view with the toothed wheel and the segment disengaged,

and neither engaged by the paper roll. Fig. 13 is a similar view showing the segment approaching the paper roll. Fig. 14 shows the 55 segment engaging the paper roll. Fig. 15 shows the extreme end of the segment engaging the paper roll. Fig. 16 shows the toothed wheel engaging the paper roll, and the wheel disengaged by the segment. Fig. 17 is an enlarged side view of the segment. Fig. 18 is a modified form of my attachment in side elevation, and Fig. 19 is an enlarged side elevation of the main features of the modification.

The same letters of reference denote the 60 same parts throughout the several figures of the drawings.

To a suitable base A are secured the base plates B having supporting flanges a and guide ways b for the supports C which support 70 and carry the ink roller D, the type inking roller E and the printing roller F. The supports C, of which there are two, one at each end of the rollers, have flanges c on their inner sides, which extend from near the tops of 75 the said arms downward to about one half their lengths; and between such flanges are located the spindles of the ink roller D, and the type inking roller E. These spindles are lettered respectively d and e.

G designates the top cross bar having right angled projections G' at each end, each of said ends having a parallel flange g on its outside throughout its length. This cross bar G is rigidly secured through the right angled projections G' to the said arms C near their tops 80 and holds the arms firmly together.

G² denotes a knife depending from the cross bar G and engaging the paper roll throughout its length, for the purpose of cutting the 85 paper off from the roll after it is printed.

The tension rod H is constructed with a U-shaped or forked lower end, and with a right angle projection having a knob h at its upper end. There are two of these tension rods, 90 one at each end of the machine.

H' denotes a coil spring secured at one end to the base plate B, and at the other end to the knob h of the tension rod H. I term this a tension spring, as it is through the medium 100 of this spring H' and the said rod H that the rollers D, E and F assume the proper relative bearing to each other and on the paper as it is pulled from the reel.

The printing roller F may be constructed of any suitable material, but I prefer to use wood, and provide the ends with brass or similar plates I, which have a series of apertures 5 i and a central spindle i' constructed so as to be journaled in a bearing f in the supports C.

The standards K are secured in a suitable supporting block or small table L and have journal sockets k in which the spindles of 10 the paper roll M, turn. These standards also support the base A in proper position above the paper roll, so that a knife of ordinary construction may be suspended from the base A down to the paper.

15 The automatic mechanism for throwing the printing roll into and out of action consists of a toothed wheel N loosely secured to the end plate I by a pin or screw m; and a toothed segment O securely pivoted to the said plate 20 I on the pin n so as to oscillate freely between the toothed wheel N, and a stop o also secured on the face of the end plate. It will be observed that the two pivot points m and n, and the stop o, have fixed positions with 25 relation to each other and to the center of the end plate I, so that they will assume the positions when the machine is in operation as in Figs. 9 to 17, of the drawings. The segment O has a series of small teeth on its periphery which catch the paper when it comes 30 in contact with it and thus promote its speed. The periphery of this segment has the same center as the periphery of the end plate i, and said periphery extends beyond that of 35 the end plate and printing roller so as to lift the printing roller or cylinder out of contact with the paper roll, and thus stop the printing. The side of the segment O nearest the toothed wheel N, has one projection or large 40 tooth P, having an angle face see Fig. 17, so that the wheel may readily turn past the said tooth or projection when not engaged therewith. It will be observed that the side of the segment where the tooth or projection P is 45 located is of the same curvature as the periphery of the wheel N, so as to set closely down on said wheel when they are engaged with each other.

50 As shown in Fig. 8 of the drawings the printing roller has parallel ribs or strips p secured to each end plate I by means of small screws p' which pass through the apertures i. Suitable spaces are left between these strips p to receive type p² which may be placed 55 therein in the usual manner. There is a large space Q which is not used for type and as there is no occasion for printing all the paper as it passes off the reel it becomes necessary to bridge over this space, which is accomplished by securing two or more bridge pieces q to the body of the printing roll F, so as to brace the ribs or strips p and protect 60 the body of the printing roller. It is for this particular purpose of preventing any printing, or the bridge pieces from blurring the paper while the paper is being drawn from the roll, that the automatic mechanism which

70 consists of the wheel N and the segment O is employed, and is placed on the end plates I just opposite and on an alignment with the space Q left blank or where there is no printing desired, for it will readily be seen that as soon as the tooth P engages the wheel N, the latter is locked and then moves the cylinder to again effect the printing.

75 V is a plate secured to the plate I, over the toothed wheel and segment, so as to protect them. As the paper is drawn quickly from the roll, the teeth of the segment pass out of engagement with the paper, because the segments are pivoted loosely on the end plates of the cylinder and the inertia of the latter is sufficient to prevent it from turning with the segments. While the segment teeth are thus rendered out of engagement with the paper, 80 the toothed wheel N is operated as long as the paper is continually pulled fast, and when it is desired to start the printing, the movement of the paper is entirely or nearly stopped, which will stop the wheel N and allow the tooth or projection P on the segment O to engage the teeth of the wheel N, and when the paper is started from the roll again, it operates the printing roller. Several different sizes of 85 these segments may be used on the same machine, according to the amount of printing desired, that is for a large amount, a small segment would be employed, and for a small amount a large segment would take the place 90 of a smaller one.

95 The operation of the device is as follows: The cylinder is raised from contact with the paper by means of the pivoted segments. Upon pulling the paper quickly the segments will first be moved forward from locking contact with the wheels N, without starting the cylinder. The further movement of the segments will cause them to strike the stops o and thereby turn the cylinder slightly to bring the wheels N into contact with the paper, which 100 wheels still keep the cylinder raised out of contact with the paper. The further movement of the paper turns the wheels on their axes without turning the cylinder until the segments drop back into locking contact with 105 the wheels, whereupon the cylinder will be turned and the printing effected.

110 In the modifications shown in Figs. 18 and 19 an ordinary pawl is substituted for the toothed segment such pawl and the wheel N 115 being respectively loosely pivoted and eccentrically mounted upon the ends of the printing cylinder, and their operation is exactly the same as in the foregoing described operation, the construction of the modified parts being as follows: A lever R is pivoted near the end of the standards K on either side of the machine, and upon the free ends of the said levers is journaled the printing roller, which has the toothed wheel N actuated and 120 controlled by the pawl r. The inking rollers are suspended over the printing roller by the free ends of two bow springs S; such free ends 125 are forked and connected by a straight bar s 130

so as to form a triangle support for the printing rollers. The other end of the spring S is securely fixed to the lever R by bolts or set screws T. When the toothed wheel N strikes the paper roll it is turned by pulling the paper from the roll, and thus the pawl r is prevented from dropping into engagement with the said wheel after the pawl has passed its center of gravity when the wheel has come 5 opposite the paper. The operation of the pawl upon the toothed wheel N is just the same as the segment, but the said pawl does not engage the paper. This construction will be found more conveniently employed in small 10 machines or where it is desired to put the machine for temporary use.

The roll paper reel, knife and guard shown and described, form no part of my invention, but what I believe to be entirely my own invention 20 is the automatic mechanism or its equivalent for accomplishing the same purpose, together with the manner of suspending the inking and type rollers above the paper roll; and in this I desire to be understood 25 as not limiting myself to the exact construction, arrangement of parts or material used, for I hereby reserve to myself the right to change the relative position and manner of constructing said parts without departing 30 from the spirit of my invention.

Having thus described my invention, what I claim is—

1. In a printing attachment for roll paper reels, the supports for the roll of paper, a printing roller movably supported to rest upon the roll, a gear wheel mounted eccentrically on each end of the roller and projecting beyond the periphery of the same, and pivoted segments having locking teeth to engage 35 said gear wheel, substantially as and for the purpose set forth.

2. In a printing attachment for roll paper reels, the inking rolls and the printing roller the supports having flanges and a bearing located 45 below said flanges in which the printing roller is journaled in combination with the tension rod having a forked end, and the tension spring secured to the tension rod, substantially as and for the purpose set forth.

50 3. In a printing attachment for the paper reels, the combination of the inking rolls and the printing roller, and means for supporting the same one above the other, said roller pro-

vided with the end plates, the toothed wheels eccentrically mounted on the end plates and 55 projecting beyond the periphery of the printing roller and the tooth segments loosely pivoted on the face of each end plate, substantially as and for the purposes set forth.

4. A printing roller for paper reels, having end plates connected by ribs or strips, a toothed wheel loosely and eccentrically mounted on the face of each of the end plates, and extending beyond the periphery of the printing roller in combination with a toothed segment 60 loosely pivoted on the face of the end plates substantially as and for the purpose set forth.

5. A printing roller for paper reels having end plates joined together by ribs or 65 strips arranged with teeth typespace between them and the bridge pieces secured to the printing roller, in combination with the automatic mechanism consisting of the toothed wheel and the pivoted toothed segment 70 secured to each of the end plates and in alignment with the said bridge pieces, said wheel eccentrically mounted on each of the end plates and projecting beyond the periphery of the printing roller substantially as and for 75 the purpose set forth.

6. In a printing attachment for printing roll paper reels, the combination with the printing roller and the inking rolls of the supports, the base plates having the supporting 80 flanges and guideways wherein the said supports are operated, the tension rods, a spring secured to each of said base plates and connected at the top of the supports to the said tension rods, substantially as shown and 85 described and for the purpose set forth.

7. The combination with a printing roller of the character described, of the end plates, and automatic mechanism comprising a toothed wheel and a toothed segment secured thereon, 90 of a stop also secured on the end plates to control the movement of the segment, and the protecting plates adapted to cover the said automatic mechanism, substantially as shown and 95 described.

In witness whereof I hereunto set my hand in presence of two witnesses.

FRANK B. KOSA.
